UNITED STATES PATENT OFFICE.

WILLIAM H. FARLEY, OF LYNCHBURG, VIRGINIA, ASSIGNOR OF FORTY-NINE ONE-HUNDREDTHS TO EDWARD G. SIGGERS, OF WASHINGTON, DISTRICT OF COLUMBIA.

COMBINATION-TROUSERS.

No. 923,845.

Specification of Letters Patent.

Patented June 1, 1909.

Application filed July 19, 1905. Serial No. 270,417.

To all whom it may concern:

Be it known that I, WILLIAM H. FARLEY, a citizen of the United States, residing at Lynchburg, in the county of Campbell and State of Virginia, have invented a new and useful Combination-Trousers, of which the following is a specification.

The invention relates to improvements in trousers.

10 The object of the present invention is to improve the construction of trousers, more especially the manner of forming the cuff at the bottom of the leg, and to provide a pair of trousers having a cuff adapted to be arranged either exteriorly or interiorly of the leg of the trousers without varying the length of the latter, whereby the trousers may be used with a cuff in summer and without the cuff in winter.

20 A further object of my invention is to provide a cuff which, when folded within the leg to conceal it, will enable the trousers to present a smooth exterior appearance unbroken by either a seam or a line of stitching around 25 the leg at the point of attachment of the cuff.

Another object of the invention is to save material in the construction of the cuff, and to provide a thin cuff in which only two thicknesses of material extend below the 30 hem seam and in which the edge of the material will be concealed within the folds of the cuff.

With these and other objects in view, the invention consists in the construction, and 35 novel combination of parts hereinafter fully described, illustrated in the accompanying drawing, and pointed out in the claims hereto appended; it being understood that various changes in the form, proportion, size and 40 minor details of construction, within the scope of the claims, may be resorted to without departing from the spirit or sacrificing any of the advantages of the invention.

In the drawing:—Figure 1 is a perspective view of one of the legs of a pair of trousers provided with a cuff, constructed in accordance with this invention, and arranged exteriorly of the leg. Fig. 2 is an enlarged longitudinal sectional view of one side of the 50 leg, the cuff being arranged as shown in Fig.

1. Fig. 3 is a similar view, the cuff being concealed within the leg. Fig. 4 is a plan view of one of the pieces of the leg, showing the same before folding, and illustrating the

lines on which the material is folded to form 55 the cuff.

Like numerals of reference designate corresponding parts in all the figures of the drawing.

1 designates one of the legs of a pair of 60 trousers provided with a reversible cuff 2, which is adapted to be worn either exteriorly of the leg, as illustrated in Figs. 1 and 2 of the drawing, or interiorly of the leg, as shown in Fig. 3, to enable the leg to present the appearance of the leg of an ordinary pair of cuffless trousers. The leg of the trousers is provided with a sufficient extension of material to form the cuff, the extension being doubled to provide a fold and the fold being doubled 65 to provide an inner fold or lining. The material is measured off to the line 3, which, before folding, is the length of the finished trousers. The material is then folded on the line 4 and laid back on the trousers a distance less 70 than the width of the cuff 2, substantially equal to one-half the width of the same, and the material is then folded and extended downward the entire width of the cuff, and is folded inward or upward on the line 5, which 75 marks the bottom of the cuff, a distance substantially equal to one-half the width of the cuff, a slight excess or extension of the material being provided at the edge 6 to enable the same to be felled to the leg within the 80 folds of the cuff at the line 4. The seam is provided at the point where the leg joins the cuff, and which is the pivot point on which the cuff turns when it is turned inside or out.

It will be seen that the combined length of 90 the upward and inward folds is substantially equal to the width of the cuff. The edge of the material is concealed within the folds of the cuff, so that the bottom of the trousers both inside and outside will present a smooth 95 appearance and not the rough edge present in the ordinary trousers. Of course, it will be understood that the edge of the material may be secured within the folds of the cuff by any suitable means, and the material of the cuff 100 may be cemented or otherwise secured together if desired. The attachment of the edge of the material to the leg of the trousers is along the center or median line of the cuff at the inner side thereof, the attached portion of the cuff forming a pivot, on which the cuff is adapted to turn to arrange it either 105

interiorly or exteriorly of the leg. The cuff is

designed to be arranged outside in summer and inside in winter, and with either position of the cuff, the trousers present the same length of leg. It will be noted by reference 5 to Figs. 2 and 3 that in either adjustment of the cuff, there are only two thicknesses of material below the seam which connects the cuff to the bottom of the leg. After wearing the cuff on the outside, it is only necessary to 10 turn it within the leg and press out the crease, and the trousers at the bottom will present the smooth exterior of an ordinary pair of trousers.

The cuff of the present invention has only 15 two thicknesses of material, and as the material is folded backward only one-half the length of the cuff at the top thereof, it will be apparent that there is a great saving of material over the formation of the ordinary cuff, 20 in which the material is folded back the entire length of the cuff. The ordinary cuff is composed of inner and outer portions the entire width of the cuff, and it is also provided with a bottom inturned portion correspond- 25 ing to the inturned portion 7, which forms the lower half of the inner side or portion of the cuff of the present invention. Also by forming the cuff as herein shown and described, the trousers are made much thinner 30 and lighter at the bottom than with the ordinary cuff.

In one aspect of the case, my invention comprehends a trousers leg having its bottom portion formed with an inward fold, the lower 35 portion of which is fastened to the interior of the trousers, and the upper portion of said fold being loose to project below the fastened portion of said fold when said fold is reversed and turned up on the exterior of the trousers.

40 Having thus fully described my invention, what I claim and desire to secure by Letters Patent, is:—

1. Trouser legs having legs provided with 45 cuffs at their bottoms, each cuff having an upward fold laid back upon the leg and of a length equal to one half the width of the cuff, and a downward fold of the entire width of the cuff, and an inward fold of a length equal to one half the width of the cuff and 50 having the edge properly secured, whereby only two thicknesses of material extend below the hem seam.

2. A trousers leg provided at its lower end 55 with an integral cuff, centrally connected to the bottom of the leg and adapted to be turned interiorly or exteriorly of the same without varying the length of the said leg.

3. A trousers leg provided at the bottom 60 with a cuff having an upward fold laid back upon the leg and of a length less than the

width of the cuff, and a downward fold the entire width of the cuff, and an inward fold having the edge properly secured at the point where the leg joins the cuff.

4. A trousers leg having an extension at 65 the bottom, said extension being doubled to provide a fold, said fold being doubled to provide an inner fold or lining, said inner fold or lining being secured to the inner surface of the first-mentioned fold at the point where 70 the leg joins the cuff, said folds forming a cuff connected at a point between its side edges to the bottom of the trousers leg and adapted to be folded either within or without the trousers leg. 75

5. A trousers leg provided with an integral reversible cuff adapted to be turned interiorly or exteriorly of the same to form either plain or cuff trousers, said cuff having an upward fold laid back upon the leg and of a length less than the width of the cuff, and a downward fold the entire width of the cuff, and an inward fold having the edge secured within the cuff, whereby it is adapted to be turned either inside or out without creasing 85 it, the combined length of the said upward and inward folds being of a length substantially equal to the length of the downward fold. 85

6. A trousers leg provided with an integral 90 cuff adapted to be turned interiorly or exteriorly of the same to form either plain or cuff trousers, said cuff having an upward fold laid back upon the leg and of a length less than the width of the cuff, and a downward fold 95 the entire width of the cuff, and an inward fold having the edge properly secured by a seam at the point where the leg joins the cuff, whereby only two thicknesses of material extend below the seam in either position of the 100 cuff, the combined length of the said upward and inward folds being substantially equal to the length of the downward fold. 100

7. A trousers leg provided at the bottom 105 with a cuff having an upward fold laid back upon the leg and of a length less than the width of the cuff, and a downward fold the entire width of the cuff, and an inward fold having the upper edge secured by a seam to the leg bottom at the point where the leg 110 joins the cuff, whereby only two thicknesses of material extend below the seam.

In testimony, that I claim the foregoing as my own, I have hereto affixed my signature in the presence of two witnesses.

WILLIAM H. FARLEY.
